UNITED STATES PATENT OFFICE.

FRANCIS M. NICHOLS, OF CHICAGO, ILLINOIS.

REPRESENTING AND MULTIPLYING MONUMENTAL AND OTHER DESIGNS.

SPECIFICATION forming part of Letters Patent No. 287,310, dated October 23, 1883.

Application filed August 6, 1883. (No model.)

To all whom it may concern:

Be it known that I, FRANCIS M. NICHOLS, of Chicago, in the county of Cook and State of Illinois, have invented certain new and useful Improvements in the Art of Representing and Multiplying Monumental and other Designs; and I hereby declare the following to be a full, clear, and exact description thereof, which will enable others skilled in the art to 10 which my invention relates to make and use the same, reference being had to the accompanying drawings, forming a part hereof, and in which—

Figures 1 and 2 represent side elevations of 15 different designs formed by joining the several cards together, as indicated. Fig. 3 represents a single card and design.

Like letters of reference indicate like parts.

The nature and object of my invention is 20 the art of producing quickly by the interchange of cards or blocks a great variety of designs for monuments, buildings, &c., by the use of a small number of cards or blocks, each having on one or more of its sides a separate 25 design complete in itself, combined by successive additions into sets, so as to form a completed structure.

In the drawings, a^2 b^2 c^2 d^2 represent blocks or stout cards joined on the lines A B, C D, E 30 F, of which the cards a^2 have on them the designs a and a' , respectively, two different designs for the base of monuments. The cards b^2 have each a die, b and b' , of different design, and the cards c^2 have each a vase of different design, c and c' . Upon the cards c^2 are 35 also shown in dotted outline the shafts d and d' , which are upon the other side of the card, or may be upon another one, and upon the cards d^2 are shown the apex e of the shaft, 40 which may be replaced by the card with the figure e' , and which card has on its opposite side the apex e^2 . The cards a^2 b^2 c^2 d^2 must all be cut of a uniform size and placed upon a 45 table, easel, or other support, so that one vertical edge shall lie against a straight edge, f , so as to bring the different parts of the structure into their proper position, and so that either die b or b' , or any other design whatever, made to the same scale for that place 50 shall fit into its proper place with the parts immediately above and below it, and the same with all other parts of a design. For monuments, the various parts shown on a card are usually made out of one stone and polished in 55 whole or in part, and are so shown.

The manner of using my invention is as follows: Starting with any given base, as a' , a suitable design for a die, as b' , is placed upon it, which may then be surmounted by an urn, c' , or a shaft, d' , and when the shaft d' is chosen it may be finished either with the apex e of Fig. 3 or with the figure e' , or with still another form of apex, e^2 , shown on the other side of the card and figure e' . We will suppose, for illustration, that we have five different cards, each of which has on its two sides a design for a die, d^2 ; also, that we have five cards, c^2 , and the same number of cards d^2 . Then, by the use of the five cards b^2 we can, on the same base, a' , produce ten different designs for that part of the monument, and that with either one of the ten cards b^2 and ten cards c^2 ten completed designs may be shown, and evidently with the two sets of cards b^2 c^2 as many designs may be shown as the cards 75 are capable of forming combinations or changes of the designs, and with such designs multiplied with the height or division of the structure into parts a very great variety of designs may be displayed with comparatively 80 very few cards, thereby not only saving great labor in making such a great number of designs as can in this way be produced, but also the capacity to produce them in a very short time. Obviously the lines A B, C D, E F 85 should only come where there is a line on the design, as at $g g$, as it would not be so convenient, for instance, to cut the die b or b' in the middle of its height, where it has no lines, so, also, with the shafts d or d' , and the same is 90 true of all the parts.

What I claim is—

1. The art or process of producing designs for purposes as herein described by executing parts of a structure each upon a separate 95 card placed in exact position so as to register with adjoining parts above and below it, and whereby with said cards combined, as described, a great variety of designs may be produced, substantially as specified.

2. The cards a^2 b^2 c^2 d^2 , provided on one or both sides with designs for like parts of a structure, and so that the said parts may be interchangeable and register so as to form various completed designs, substantially as specified.

FRANCIS M. NICHOLS.
